(57) **CLAIM**

The ornamental design for a carrying case with attachment, as shown and described.

DESCRIPTION

FIG. 1 is a front perspective view showing my new design;

FIG. 2 is a front view thereof;

FIG. 3 is a right side view thereof;

FIG. 4 is a rear view thereof;

FIG. 5 is a left side view thereof;

FIG. 6 is a top view thereof;

FIG. 7 is a bottom view thereof;

FIG. 8 is an environmental view thereof; and,

FIG. 9 is an environmental view thereof.

The evenly spaced broken lines showing stitching and the dot dash dot dashed broken lines showing a portion of a belt are for the purposes of illustrating environment and form no part of the claimed design.

1 Claim, 7 Drawing Sheets
